UNITED STATES PATENT OFFICE.

JOSEPH LANE WRIGHT, OF WASHINGTON, DISTRICT OF COLUMBIA, ASSIGNEE, BY
MESNE ASSIGNMENTS, TO FREDERICK C. STEVENS, OF ATTICA, NEW YORK.

TELEPHONE-EXCHANGE SYSTEM.

1,117,297.

Specification of Letters Patent. Patented Nov. 17, 1914.

Application filed May 18, 1906. Serial No. 317,458.

To all whom it may concern:

Be it known that I, JOSEPH LANE WRIGHT, a citizen of the United States, residing at Washington, in the District of Columbia, 5 have invented certain new and useful Improvements in Telephone-Exchange Systems, of which the following is a specification.

My invention relates to telephone exchange systems and especially to the type known as full automatic, and the object of my invention is the provision of means for reducing the number of contacts and simplifying the switches commonly known as the 15 first and second selector switches or even third selector switches, depending, of course, on the size of the exchange.

Most switches in automatic systems have two motions, either a vertical motion for 20 picking out the desired group and then a rotary motion for picking out an idle contact in this group, or first a rotary motion and then a vertical motion. I eliminate this double motion by inserting a switch which 25 I will call a primary selector between the various selector and connector switches. The switches known ordinarily as first and second selector switches, etc., and only containing ten sets of contacts, simply respond 30 to the impulses from a subscriber's sender at the substation and the wipers then come to rest on contacts leading to contacts in the banks of a group or set of primary selector switches. The wipers of the selector switch 35 resting on these contacts start the primary selectors rotating to pick out or find the calling selector switch. This operation is repeated throughout the various switches until the connector switch is reached which 40 is thereupon operated and picks out the desired line in the ordinary manner. By cutting down the mechanism of these switches and also the number of contacts, I have simplified them to a large extent, and also 45 make quite a saving in the number of relays required to operate the switch.

Specifically stated, my invention consists in the use of single motion first and second selector switches and by the introduction of 50 primary selector switches which test back to find the calling switch. In the accompanying drawings I have shown the shaft or spindle of these various primary selector switches being rotated by a stepping magnet controlled by the first and second selector

switches. Instead of operating them by this method, I may have the various spindles driven in any other desired manner. I consider the method shown preferable as the 60 switches then are only in motion while being actually used. In my invention instead of having the first and second selector switches pick out the desired group and then an idle contact in the group, I have them pick out a contact and then an idle primary 65 selector of the group pick out the contact. In other words, the testing is done in reverse order to that ordinarily used, and this system may properly be called an automatic system employing a back test.

My invention is illustrated in the accompanying drawings wherein—

Figure 1 shows a subscriber's station with a central office equipment, a primary selector switch, and a first selector switch. Fig. 75 2 shows a primary selector switch and a second selector switch. Fig. 3 shows a primary selector switch and a connector switch.

Referring now to Fig. 1, the subscriber's station A is equipped with apparatus usual 80 in common battery installations, consisting of transmitter T, receiver R, hook H, ringers Q, condenser C, and in addition a sending device P for transmitting impulses for operating the switching mechanism at central. 85 The subscriber's line terminates in a central office on a line relay L through the normally closed contacts of a cut-off relay M. When this relay L is energized, it closes the circuit of the vibrating magnet D of the primary 90 selector switch which upon operation causes the spindle Z to rotate. I mount upon the spindle a sufficient number of primary selector sets, and provide in conjunction therewith a corresponding number of trunks, to 95 properly handle the maximum number of simultaneous incoming calls. Connective apparatus equal to ten per cent. of the lines is usually found sufficient, and this sometimes falls to five. The multiple contacts of 100 the line extensions designed to be engaged by the wipers of the several sets in each group have been shown conventionally opposite the wipers w, w' and w'', but I have not shown the multiple switches, because this 105 would needlessly complicate the drawing. Neither have I indicated in the drawings the exact number of lines multiplied into each primary selector switch bank, because this is not fixed, but may be varied at will. The 110

number of primary selectors may be more or less than that of the number of conductors, depending upon the extent to which the lines are used for calling or called by others. In 5 an exchange serving more than one hundred lines, it is customary to divide them into groups of one hundred, each group being served by ten, more or less, primary selector switches having a common spindle Z . It has been found (and this forms no part of my 10 present invention), that interference between several primary selectors driven by a common motor can be avoided by spacing them apart angularly, or otherwise arranging them on the spindle, assuming the multiples of the same lines to be vertically above each other, or conversely by arranging the multiples of the lines so they will not be in vertical columns, and having all of the switch 15 wipers in line. Such arrangements are recognized by me as forming a part of the prior art, and therefore available in using my system commercially. Another feature which has been known before my invention is that 20 of preventing the subscriber from sending impulses before he has become connected with a trunk. The simplest way to avoid this is to speed up the switches, and it has been found practical with a power driven 25 switch to test one hundred contacts in less than three seconds. The time consumed by a subscriber in taking down his receiver, adjusting the same to his ear, and grasping the sending device, is never less than three seconds, and is usually considerably more. 30 However, such means to this end may be provided without affecting the present invention. On the spindle Z is carried a loose fitting sleeve Z^{10} carrying the wipers w , w' and w'' . This sleeve revolves with the spindle by means of the pin z' which is rigidly attached to a collar z^3 fastened to the spindle Z . There is a similar collar z attached to the sleeve Z^{10} which has a small hole or perforation 35 in which the pin z' normally rests. When the double wound magnet G is energized, its armature g lifts the sleeve Z^{10} out of engagement with the pin z' and the sleeve itself thereupon will cease to rotate, being 40 loose upon the spindle and held firmly by the upward thrust of the lever g and friction of the wipers upon the lower side of the contacts. Battery is supplied to the trunk wires 45 5 and 6 and from there to the calling subscriber through the windings of the two relays S and S' . The relay S controls the two solenoids E and E' , the solenoid E' through its back contact and the solenoid E through its front contact. The solenoids or slow acting 50 relays respond readily to quick makes and breaks of the contacts in the relay S . While these relays draw up the cores e^{10} and e^{20} very quickly, they drop back very slowly, so it follows that when a set of impulses are 55 sent in from the subscriber's station affect-

ing the relay S , both solenoids or relays draw up their cores which remain drawn up while the impulses are being transmitted. Between each set of impulses there follows a momentary closure of the line being due to 60 the act of the subscriber setting up another set or number and during this interval the relay S remains energized keeping the solenoid E' energized, while the solenoid E becomes deenergized and its core dropping 65 down closes the contact springs e and e' sending a rotary impulse to the switching mechanism. The magnet D' responding to the impulses sent from the subscriber's station causes the spindle Z' to rotate. This 70 spindle carries wipers w^3 , w^4 , w^5 , w^6 , w^7 , and w^8 . These wipers pass over a set of contacts leading to a primary selector switch which is connected to trunk wires leading to a second selector switch. There are only ten sets 75 of these contacts in the banks of the first selector switch Z' , this being the only number required, for instead of the first selector switch itself picking out an idle trunk, I simply step it around to the first numeral of 80 the desired line and thereafter a primary selector switch attached to a second selector switch steps around its wipers and picks out the contacts upon which the wipers of the first selector switch rest. It will be seen 85 from this method that instead of the first selector switch picking out an idle trunk, I have an idle trunk pick out the first selector switch. I introduce this primary selector between each selector and connector switch 90 and by doing so cut down the number of contacts in each switch, and instead of having a selector switch make two motions such as would be required to pick out the desired row and then pick out an idle contact, in my 95 system I simply have to make a rotary motion over ten sets of contacts. Referring to the wipers mounted on the sleeve Z^{10} , I have the wiper w wipe over the contacts while revolving so as to pick out the calling line. 100 The wipers w' and w'' while sweeping over the contacts, do not touch them until the calling line is actually picked out and when this happens the magnet G becomes energized, and lifting the sleeve, brings the 105 wipers w' and w'' into engagement with the desired line. I make this arrangement so as to prevent annoying clicks to the various subscribers whose lines may be busy. 110 Referring now to Fig. 2, the primary selector switch is the same as that already described in Fig. 1 with the exception that I have added a release or holding magnet W' . The armature w of this magnet engages the tooth z^4 when the sleeve Z^{20} is lifted up by 115 the magnet G' and holds it in that position. In this switch the trunk wipers w^{15} and w^{16} while sweeping over the contacts do not engage them until the sleeve Z^{20} has been lifted by the magnet G' . The second selector 120

125 130

switch is the same as the first selector with the exception that I have added a relay S^2 to the trunk wire 11 for operating the rotary magnet D^2 .

6 Referring now to Fig. 3, the primary selector switch is the same as already described in the foregoing figures. The connector switch is a two-way switch, that is to say, it has both a vertical and a rotary movement. In this present system, I make the rotary movement first. The rotary magnet D^6 is controlled by the relay S^3 which is connected to the trunk wire 15 through the normally closed contacts of the relay S^5 .
 10 The relay S^4 is connected to the trunk wire 16 through the normally closed contacts of the relay S^6 . The first impulse or working of this relay S^4 closes the circuit of the vertical magnet D^6 by the following path: battery, 78, 92, D^6 , 91 x , x' , 93, s^{11} , s^{12} , ground. This causes the spindle Z^6 to take one step. This step removes the rotary magnet D^6 from under the control of the relay S^3 and in its place connects the vertical magnet D^5 . This transfer takes place through the contacts x^3 , x^4 and x^5 . The second set of impulses coming in affecting the relay S^3 , now operates the magnet D^5 , causing the spindle to step up vertically. The 20 first vertical movement of the spindle after the false movement caused by the relay S^4 as already described, operates the contact springs x , x' and x^2 . The operation of these springs removes the magnet D^5 from under control of the relay S^4 and in its place connects the bridge relay J . The second rotary impulse now coming in closes the circuit of this relay J which thereupon locks itself, completing the trunk wires 17 and 18 respectively through to the trunk wipers w^{40} and w^{41} . The operating of this relay also disconnects the vertical magnet D^5 and in its place connects the ringing relay K . The release magnet W^4 has a U-shaped armature, 30 one arm of which normally engages the vertical teeth, while the other arm engages the rotary teeth of the spindle Z^5 . The energizing of this magnet allows the spindle to drop and then rotate, assuming its normal position. Battery is supplied to the called subscriber through the retardation coil I and the relay S^8 . The relay S^8 , becoming energized when the called subscriber answers, disconnects the relays S^9 and S^{10} and 35 short-circuits the condensers C^3 and C^4 respectively. This is simply done for talking purposes as it removes the bridges and condensers from the line.
 40 The operation of my system is as follows: The subscriber at station A, desiring to make a call, removes his receiver. The line circuit being thus closed causes the relay L to become energized, closing the circuit of the magnet D . The operation of this magnet causes the spindle Z to rotate. The 45

wiper w of the first set making connection with the busy contact, closes the circuit of the magnet G by the following path: battery B, 25, 24, 1, 1', 45, w , one winding of the magnet G to ground. The operating of the magnet G lifts the sleeve Z^w , bringing the wipers w' and w^2 in connection with their contacts, closing the circuit of the cut-off relay M in series with the relay S' . The energizing of the relay M disconnects the relay L , removing battery from the busy contact upon which the wiper w rests. The circuit of the magnet D is also open and the spindle z will cease to rotate unless some other party happens to be calling in at that instant, in which case the circuit of the magnet D would be kept closed by some other line relay. The relay S becoming energized by current flowing through the circuit B, 25, 26, S' , 6, 4, 2, 50 substation, 1, 3, 5, S and ground, closes the circuit B, 25, 26, s^8 , 28, s' , 29, E' and ground of the solenoid E' which in turn holds the relay G energized through its second winding by the following path: battery B, 25, 55 36, 47, e^5 , e' , 40 G to ground. The calling subscriber is now connected to the first selector switch and sets his number wheel to the desired number. This wheel in running down makes and breaks the contacts p and p' which operates the relay S . The operation of this relay closes the circuit of the solenoid E which draws up its core and remains energized while these impulses are being sent. The relay S being responsive 60 to the makes and breaks of the subscriber's station, closes the circuit of the magnet D' by the following path: battery B, 25, 24, 26, s^3 , s^4 , 28, s' , s , 27, e^2 , e^3 , 30, 7, 32, D' , 31, f , f' to ground. The magnet D' operating causes the spindle Z' carrying the wipers to rotate a number of times corresponding to the impulses sent. The calling subscriber is now connected to contacts in the banks of the primary selector switches and it 65 only remains for an idle primary selector switch to pick out the first selector switch. This act is brought about as follows: the wiper w^3 closes the circuit of the vibrating magnet D^2 by the following path: battery B, 36, f^2 , f^3 , 34, w^3 , 41, D^2 to ground. This magnet, starting up, causes the spindle Z^2 carrying the wipers belonging to sets of 70 primary selector switches to rotate. The wipers of the first set coming in connection with the busy contacts have the circuit of the magnet G' closed by the following path: battery B, 36, f^2 , f^3 , 38, w^1 , 43, w^1' , 51, G' to ground. The operation of this magnet lifts the sleeve Z^{20} and brings the trunk wipers into connection with the trunk contact, and at the same time the circuit of the relay F , Fig. 1, is closed through the wiper w^{11} , thus disconnecting the magnet G' . The 75 sleeve Z^{20} is kept in position by the arna- 80

ture w of the magnet W' engaging the tooth e^4 . The calling subscriber is now connected to a second selector switch and proceeds to set his number wheel for the second set of impulses. These impulses coming in operate the relay S^2 which in turn closes the circuit of the magnet D^2 , causing the spindle Z^2 carrying the wipers, to rotate and come opposite contacts in the banks of primary selector switches which are connected to connector switches containing the contacts of the desired line.

The operation of the primary selector in Fig. 3 is identical with that already described and need not be gone into in detail. The sleeve Z^{20} is now held up by the armature of the magnet W^2 . The calling subscriber is now connected through to a connector switch and proceeds to set his number wheel for the third set of impulses. These impulses coming in operate the relay S^3 which in turn closes the circuit of the rotary magnet D^3 by the following path: ground, $s^3, s^1, 87, j^2, j, 77, s^4, s^3, 81, D^3, 73, 25$, to battery B. The operation of the magnet D^3 causes the spindle Z^3 carrying the wipers, to rotate and come opposite a row containing the contacts of the desired line. Between every set of impulses as stated in the description, the core of the solenoid E drops down and a momentary impulse is placed on the rotary side of a trunk by the following path: battery B, 25, 26, $s^3, s^4, s^1, s^2, 20, 48, s^1, s, 27$, to 8, (the rotary side of the trunk). This rotary impulse was not needed in connection with the first and second selector switches, but is utilized in the connector switches. This rotary impulse now coming in to the connector switch by way of wiper w^{10} , trunk wire 16, 85, 86, S^4 and ground, operates the relay S^4 which in turn closes the circuit of the vertical magnet D^4 by the following path: ground, $s^{12}, s^{11}, 93, s^7, s, 91, D^4, 92, 78, 25$ to battery B. This momentary impulse causes the spindle to make one vertical movement, the action of which opens the contacts s^3 and s^4 , disconnecting the magnet D^3 and closing the contacts s^4 and s^5 , connecting the magnet D^4 in its place. The calling subscriber now sending in the fourth set of impulses, operates the relay S^5 which now in turn operates the vertical magnet D^5 , causing the spindle Z^5 to step up vertically and bringing the wipers in connection with the contacts leading to the desired line. The first vertical movement of the switch under the influence of the relay S^5 opens the contacts s and s' , and closes the contacts s' and s^2 , disconnecting the magnet D^5 from the wire 93 and connecting the relay J thereto. The rotary impulse now coming in, operates the relay S^6 which in turn closes the circuit of the relay J by the following path: ground, $s^{12}, s^{11}, 93, s^7, s^6, s^5, 20, J, 79, 78, 25$ to battery B.

This rotary impulse also connects the test relay P to the tip side of the line by the following path: ground, $s^{10}, s^9, 73, P, 74, 21, w^{10}$, to the tip side of the line. If the called line were busy there would be battery or a difference of potential which would energize the relay P and close the circuit of the release magnets W^2 and W^4 , restoring the switch to its normal position. We will take it for granted that the called line was not busy. Then the energizing of the relay J would complete the trunk circuit through the called line. The operation of the relay J disconnects the magnet D^4 and in its place connects the ringing relay K. The relay J remains energized or locked through the contacts v and v' of the relay Y which itself remains energized in series with the relay F', Fig. 2. This relay F' disconnects the relay S^2 from ground, thus removing a tap from the vertical trunk wire. The calling subscriber now sends in a set of impulses for ringing, operating the relay S^2 which in turn operates the ringing relay K. The ringing relay K attracting its armature, disconnects the calling end of the trunk and supplies generator current to the called end, thus ringing the bells of the desired party. The called party upon answering closes the circuit of the relay S^6 which in turn short-circuits the condensers C^2 and C^4 , and disconnects the vertical and rotary relay S^2 and S^4 . The called subscriber's equipment is precisely the same as that of the calling subscriber in Fig. 1, part of the line multiples indicated in that figure being contained in the banks of the connector switch Z^5 . The circuit of the relay S^6 may therefore be traced as follows: B (Fig. 3), 25, 105 76, 1, 18, $j^2, j, 20$, contacts of ringing relay, 22, w^{11} , sleeve contact of the line as shown in Fig. 1, 4, $m^5, m^4, 2, p^1, p, T, R, H, 1, m^1, m^2, 3$, multiple tip contact, w^{10} (Fig. 3), 21, 19, $j^3, j^2, 17, S^6$ and ground. The subscribers are now supplied with a straight talking circuit with one pair of condensers in the first selector switch and relays with bridged battery on either side for supplying talking current. It will be noticed in Figs. 1, 2 and 3, the release magnets W, W', W^2, W^3 and W^4 are connected to a common release wire 39 in the first selector switch through their various wipers. At the end of the conversation, the calling subscriber hanging up his receiver, deenergizes the relay S, disconnecting the solenoid E'. The core of this solenoid upon dropping, closes together the contacts e^1 and e^2 , placing battery on the wire 39 which thereupon energizes the release magnets in the various switches, restoring them to their normal or idle positions. The dropping of the core of the solenoid E' opens the contact springs e^1 and e^2 , disconnecting the relay G which in turn 120 125 130 135 140 145 150 155 160 165 170 175 180 185 190 195 200 205 210 allows the sleeve Z^{10} , carrying the wipers, to assume its normal position, disconnecting the cut off relay M and again placing the line relay L under control of the calling subscriber.

Having thus described my invention what I claim and desire to secure by Letters Patent of the United States is:

1. In a telephone exchange system, the combination with a plurality of subscribers' stations having impulse senders and a central station comprising groups of impulse receiving switching devices, and interposed switching devices between the lines and the first group of impulse actuated switches, and between each successive group of such switches, each interposed device being adapted to test for a calling unit in a preceding group and connect the same to its associated unit in its own group.

2. In a telephone exchange system, the combination with a plurality of subscribers' stations and a central station, of lines interconnecting them, means to close the respective lines in calling to cause primary impulses, sending devices to produce successive impulses, switching mechanism at the central station for receiving the primary impulses, groups of switching mechanism for receiving successive impulses, and test switches interposed between the lines and the first group of impulse actuated switches, and similar test switches associated with each successive group, said interposed testing switches being irresponsive to any impulses received after the first or starting impulse.

3. In a telephone exchange system, the combination with a plurality of subscribers' stations having impulse senders and a central station, of a trunk line there at, a first selector switch therein, a second selector switch therein, a connector switch for picking out the wanted subscriber, and interposed switches adapted successively to test for and interconnect the impulse actuated selectors to the connector switch.

4. In a telephone exchange system, the combination with a plurality of subscribers' stations having impulse senders and a central station, of connecting trunks therein, a first selector switch therein, a second selector switch therein, a connector switch for picking out the wanted subscriber, a switch between the trunks and lines, a testing switch between the first and second selector switches, and a testing switch between the second selector switch and the connector switch, all of said testing switches being irresponsive to the impulses which affect the before mentioned switches.

5. In a telephone exchange system, the combination with a plurality of subscribers' stations having impulse senders, and a central station, of impulse actuated selecting

devices, line testing and selecting means, and a plurality of associated but independently operable switches interposed between the impulse actuated switches for testing preceding links in succession, and interconnecting them.

6. In a telephone exchange system, the combination of a subscriber's station having an impulse sender, switching means at the central station having vertical and rotary operating mechanism, means controlling the vertical impulses to said switching means adapted when released to send a false impulse thereto, means controlled by said false impulse for operating the switch in a vertical direction, and means controlled by the spindle of the switch whereby the rotary operating means is rendered inoperative and the vertical switch operating means is thrown into action.

7. In a telephone exchange system, a plurality of line circuits, with two-motion automatic switches for interconnecting them, each line having means associated with it to send impulses for effecting the two motions of the switch, each switch comprising a spindle adapted for vertical and rotary movement, means for moving the switch vertically, means for rotating the switch, and means controlled by the spindle thereof for rendering one of said means inoperative and the other operative.

8. In a telephone exchange system, a plurality of line circuits provided with means for sending impulses, automatic switches for interconnecting the lines, each switch having separate means, impulse controlled for operating it in a rotary and in a vertical direction, and means controlled by the spindle of the switch for rendering either one of said switch operating means inoperable and the other operative.

9. In an automatic telephone system, the combination with a subscriber's station having a vertical and rotary impulse sender and a central station, of switching mechanism for connecting the subscriber with the wanted line, means controlled by the vertical impulses for rotating the switch, means controlled by the vertical impulses for moving the switch in a vertical direction, means operated intermediate of the before mentioned steps by the rotary impulse for giving the spindle of the switch a false vertical movement, and means under control of the spindle for transferring the operation of the rotary controlling means to the vertical controlling means.

10. In a telephone exchange system, subscribers' substations provided with impulse sending devices, a central office, a plurality of automatic switches located at said central office and operated by impulses from said sending devices for interconnecting said substations, interposed switching devices irre-

responsive to the impulses from said impulse senders, certain of said interposed switching devices operating to selectively effect connection with the calling line, other of said interposed switches operating to effect a connection with a previously energized automatic switch, and means, acting when the calling subscriber hangs up his receiver, for effecting a disconnection and a restoration of said switches and interposed connecting devices to their normal condition.

11. In a telephone exchange system, subscribers' stations provided with impulse sending devices, a central office provided with automatic switching mechanisms controlled by the impulses from said sending devices for effecting a talking connection between the substations, and interposed switching devices irresponsive to said impulses, certain of said switching devices operating to effect the connection of a calling line with one of said automatic switching mechanisms and other of said interposed devices operating to effect connections between said automatic switching mechanisms.

12. In a telephone exchange system, the combination with a plurality of subscribers' stations having impulse senders, of link circuits each provided with impulse actuated automatic switching mechanism, and interposed switching devices irresponsive to impulses from said senders for effecting a connection between a calling subscriber's substation and each successive link and its automatic switching mechanism.

13. An automatic telephone system including telephone lines, a connector adapted to make connection directly with said lines,

a trunk circuit at the exchange for interchangeable use by calling lines in establishing connections, selective switching mechanism individual to said connector, means for starting the same from a calling line, and automatic test devices for said mechanism enabling it to automatically seek out and connect with said trunk circuit, whereby said connector is connected with said trunk circuit.

14. In a telephone exchange system the combination with a plurality of subscribers' stations having impulse senders and a central station, of a trunk line at the central station, an impulse actuated selector in said trunk, a connector switch for picking out the wanted subscriber and an interposed switch adapted to test for and interconnect the impulse actuated selector to the connector switch.

15. In a telephone exchange system the combination with a plurality of subscribers' stations having impulse senders and a central station, of a connecting trunk, a selector switch and a connector switch for picking out the wanted subscriber, a test switch between the trunk and lines, a testing switch between the selector switch and the connector switch, all of said test switches being irresponsive to the impulse which effect the before-mentioned switches.

In testimony whereof I have signed my name to this specification in the presence of two subscribing witnesses.

JOSEPH LANE WRIGHT.
